COLD WEATHER GOGGLES

William R. Christensen, Newton Highlands, and
Chester E. Cross, East Sandwich, Mass.

Application June 8, 1949, Serial No. 97,863

6 Claims. (Cl. 2—14)

(Granted under the act of March 3, 1883, as
amended April 30, 1928; 370 O. G. 757)

1

The invention described herein, if patented, may be manufactured and used by or for the Government for governmental purposes without the payment to us of any royalty thereon.

This invention relates to an improvement in goggles structure and, more particularly, to an improvement in anti-fogging and anti-frosting goggles structure.

It has heretofore been known that a goggles structure to be used under conditions of low ambient temperatures operates more efficiently when a continuous new air flow is produced, through either the goggle lens or the goggles frame. It has been discovered, however, that enclosed goggles lens may be made to perform without detrimental fogging and frosting under low temperatures when the goggles are airtight and have no renewal of fresh air from an outside source.

Accordingly, it is an object of this invention to provide an improved means for cooling and dehumidifying the air within the space confined by the eyecups of a goggles to lessen or prevent fogging or frosting of the lens of the goggles in cold weather.

It is another object of this invention to provide an improved goggles in which dehumidification and cooling of the air trapped in the frame behind the lens is affected by means of condensers.

It is a further object of this invention to provide improved goggles including air cooling and dehumidifying means so arranged that air trapped by the eyecups of the goggles is conventionally circulated and recirculated through the cooling and dehumidifying means and the eyecup cavities of the goggles.

It is an additional object of this invention to provide an improved anti-fogging and anti-frosting goggles structure in which undue chilling of the eyes is prevented.

Further objects, advantages, adaptations and uses of this improvement in goggles structure will be readily apparent from the accompanying drawings, wherein:

Figure 1 is a front elevational view of a goggles structure embodying the invention;

Figure 2 is a cross-sectional view, on line 2—2, of Fig. 1; and

Figure 3 is an exploded fragmentary perspective view of a goggles condenser.

Referring to the drawings, goggles frame 10 is of a conventional character, having the usual face-contacting side 11 and a conventional lens-holding bead 12, connected together by a web 13.

2

The bead 12, being of conventional character, is of flexible nature and is provided with a groove 14, within which is adapted to be fitted a conventional lens 15. The lens 15 is further secured within the groove 14 and held to the goggles frame by conventional snap fasteners 16. The goggles frame 10 is further provided with a conventional head strap 17, threaded through ears or lugs 18 and secured in the T-grooves 19 of lens 15 in conventional manner. Further, the frame structure 10 is provided with a flexible nose covering 20 and additional padding 11', of chamois or the like, secured to the side portion 11 by a suitable rubber adhesive material or the like.

Sealed at their lower edges in the top side of the web 13 are a plurality of air cooled condensers 21 which are formed from thin, flexible metallic sheeting 22, folded or bent to provide a plurality of accordion-like oppositely disposed uniformly spaced internal vertical fins 23 (Fig. 3) on the front and rear walls the inner ends of which fins are closely spaced. There is likewise formed, by bends or accordion folds in the strip 22 a plurality of external vertical fins 24, positioned at uniformly spaced intervals across the front side of the condensers 21. Similar fins 24' are provided at the ends of condensers 21, the sides of the forward fins 24' being spaced from each other and positioned in alignment with the spaces between the inner ends of internal fins 23 at the approximate center of the condensers. The strip 22 is shaped into rectangular box-like form, as shown in Fig. 3, and its overlapping ends are sealed by soldering or a suitable rubber or resinous adhesive. A cover plate 23' is sealed in the same manner to the top edges of the side walls of the condenser to provide an airtight chamber through which air may circulate from the goggles cavities in the manner hereinafter described.

Positioned within the condensers 21, between the vertical fins 23 and supported by fins 24', is a partition plate 25 extending approximately three quarters of the vertical height of condensers 21. This partition plate 25 also extends at its lower end 25' slightly below the bottom edge of condenser 21 and is further provided with lateral edge portions 25'', which fit between the sides of fins 24' to hold the partition in position.

In order to position the condensers 21 in the goggles frame 10, there is provided in the web 13, a plurality of rectangular slots or openings 26 for receiving the bottom edge of the con-

densers and grooves 26', for receiving the fins 24', as shown in Fig. 3. Further to provide a smooth fit between condenser 21 and web 13 on the front side of the frame 10 the lower ends of front fins 24 are cut at a point spaced from the bottom edge of the condenser a distance approximately equal to the depth to which the condensers 21 are to be inserted within the rib 13. The severed lower ends of the fins 24 are folded against the rectangular side of the condenser body as illustrated by 21' in Fig. 3.

The condensers 21 are sealed in the openings in web 13 by an appropriate adhesive in the nature of rubber, resin, cellulose acetate, or the like. A transparent partition 27 is mounted within the eyecup portions of the goggles frame and rests against the lower end 25' of partition plate 25 along its upper edge while its lower edge rests against the inner edge of bead 12. A sponge rubber molding 28 is provided between the side 11 of goggles frame 10 and partition 27. The partition 27 is provided adjacent its lower edge with a plurality of openings 29 which permit circulation of air as hereinafter described.

With the lower edges 21' of the condenser structures 21 fitted and sealed in openings 26, and the partition 27 mounted in the manner described, the goggles frame 10 is adapted to be fitted tightly about the eyes of the wearer. When so fitted, the interior heating of the eyecup portions of the goggles causes internal convection currents to conduct moisture-laden warm air from the area adjacent to the eyes into the rear portion of the condensers 21. By reason of the comparative coolness of condensers 21 and the high thermal conductivity of the internal and external vertical fins 23, 24 and 24', a rapid change of temperature in the air current is induced. This change of temperature causes condensation of the moisture contained in the air, which deposits on the interior of the condenser walls and internal fins 23. The air is thus relieved of its moisture as it rises by virtue of convection currents therein and flows over the partition plate 25, whence it passes downwardly past the front fins into the space 30 provided between lens 15 and partition 27. With the openings 29 being provided substantially across the full length of the lower portion of the partition 27, the air continues to move out of the space 30 between the lenses into the area about the eyes, termed the eyecup cavity, where it again is heated absorbs moisture and repeats the cycle of flow through the condensers 21.

With the apparatus thus described it will be obvious that a continuous internal air-circulating means has been provided, which rapidly and readily removes moisture from the air contained within the goggles cavity. This removal of moisture prevents its condensation on the goggles lenses, and thereby permits the wearer to have clear, unobstructed vision for relatively long periods of time. In actual tests, it was found that this type of goggle structure remained clear from fogging and frost deposits under the following conditions:

1. For periods of one hour tests, at 0° F. and a 3 M. P. H. wind;
2. For 60 and 100 minute tests, at minus 10° F. in a 3 M. P. H. wind;
3. For 52 minutes at minus 48° F. in a 3.5 M. P. H. wind; and
4. For 29 minutes, at -60° F. in a 3.5 M. P. H. wind.

whereas available commercial goggle structures become foggy and frosty almost immediately when subjected to similar conditions.

Broadly, it may be indicated that the structure, as above described, provides a plurality of air-tight condensers on a goggles structure with substantial heat conducting and contact surface area for air entrapped within a closed goggles frame. Further, that the condenser units may be molded with, or formed as a separate attachable unit of suitable heat conductive material or materials, in the nature of copper, brass, aluminum and the like, or otherwise of less heat conductive materials in the nature of thermoplastic resins and the like. In addition, one or more of the units may be utilized with the goggles frame structure by suitable enlargement and arrangement on or with the goggles eyecup cavities, with or without some sacrifice of structure flexibility. 10 In accordance with the patent statutes, the foregoing is a description in detail of what is now considered to be the preferred form of the invention, but it will be obvious that various changes may be made in the structural details 15 without departing from the spirit of the invention, and it is intended that all such changes be included within the scope of the appended claims.

We claim:

1. In an anti-fogging and anti-frosting goggles having a flexible lens and a flexible frame to hold the lens and to cooperate therewith and with the face of a wearer of the goggles to isolate a substantially sealed space around the eyes of the wearer, means for maintaining a flow of relatively cold dry air adjacent the inner side of said lens including one or more air dehumidifying and cooling condensers projecting outwardly from said frame in sealed relation thereto, said condensers having an air cooling and moisture condensing passageway arranged to maintain a convectional flow of air from and to the sealed space when the goggles are worn for cooling and dehumidifying the air, the discharge from said passageways being adjacent the inner side of said lens.
2. In an anti-fogging and anti-frosting goggles having a flexible lens and a flexible frame for holding the lens and for cooperating therewith and with the face of a wearer to isolate a sealed space around the eyes of the wearer, air dehumidifying and cooling condensers along one edge of said frame, each of said condensers comprising a housing having an open end sealed in an aperture in said frame, partitioning means to define a plurality of vertical passages in the housing intercommunicating adjacent their upper ends and air deflecting means cooperating with the partitioning means in said condenser and with said lens to effect convectional flow of air from the space in the goggles containing air adjacent to and warmed by contact with the wearer's face through the condensers and along the inner side of said lens back to the said warmed air space in the goggles at a point spaced from the condenser.
3. In an anti-fogging and anti-frosting goggles having a flexible lens and a flexible frame for holding the lens and for cooperating therewith and with the face of a wearer of the goggles to define a substantially sealed space around the eyes of the wearer, a transparent partition in said frame cooperating with the lens to define a relatively narrow space behind the said lens communicating adjacent one edge of the frame with the portion of said sealed space containing air in contact with the wearer's face, and one or

more air dehumidifying and cooling condensers sealed in and projecting outwardly from one side of said frame, said condensers having air cooling and moisture condensing passageways arranged to maintain a convectional flow of air from and to the sealed space when the goggles are worn for cooling and dehumidifying the air, the discharge end of said passages communicating with said narrow space opposite the place at which the two spaces in the frame are in communication.

4. In an anti-fogging and anti-frosting goggles having a flexible lens and a flexible frame for holding the lens and for cooperating therewith and with the face of a wearer of the goggles to define a sealed space around the eyes of the wearer, a transparent partition cooperating with the lens to define a closed space to the rear of the said lens communicating adjacent its lower end with the space behind the partition, a plurality of air dehumidifying and cooling condensers sealed in and projecting upwardly from the top side of said frame, said condensers each having vertically extending passageways intercommunicating adjacent their upper ends only, certain of said passages communicating at their lower ends with the space behind the partition containing air warmed by contact with the wearer's face so that convectional currents of warmed air rise into the condenser through said passages and other of said passages communicating at their lower ends with the space between the lens and partition for directing cooled and dehumidified air in the condenser downwardly into the space between said lens and partition.

5. In an anti-fogging and anti-frosting goggles having a flexible lens and a flexible frame for holding the lens and for cooperating therewith and with the face of a wearer of the goggles to define a sealed space around the eyes of the wearer, a transparent partition cooperating with the lens to define a closed space to the rear of the said lens communicating adjacent its lower end with the space behind the partition, a plurality of air dehumidifying and cooling condensers sealed in and projecting upwardly from the top side of said frame, said condensers each having vertically extending passageways intercommunicating adjacent their upper ends only, certain of said passages communicating at their lower ends with the space behind the partition containing air warmed by contact with the

wearer's face so that convectional currents of warmed air rise into the condenser through said passages and other of said passages communicating at their lower ends with the space between the lens and partition for directing cooled and dehumidified air in the condenser downwardly into the space between said lens and partition, said condensers each being short in extent relative to the longitudinal extent of the top side of said frame and being spaced from each other so that flexibility of the frame is not appreciably diminished thereby.

6. In an anti-fogging and anti-frosting goggles having a flexible lens and a flexible frame for holding the lens and for cooperating therewith and with the face of a wearer of the goggles to define a substantially sealed space around the eyes of the wearer, a transparent partition in said frame cooperating with the lens to define a narrow space behind the same communicating with the space in said frame to the rear thereof containing air in contact with the wearer's face adjacent the bottom of the frame, one or more air dehumidifying and cooling condensers projecting upwardly from the top side of said frame in sealed relation thereto, said condensers each comprising a generally rectangular box-like housing of relatively thin sheet material bent to form a plurality of heat exchanging external and internal fins, the inner ends of the internal fins being relatively closely spaced, and a partition disposed between the inner ends of said internal fins, the latter and said transparent partition cooperating to define a plurality of air cooling and moisture condensing passages in said housing intercommunicating adjacent the upper end of the latter through which warm air convectionally flows upwardly from the space in said frame containing air warmed by contact with the wearer's face and downwardly into the narrow space upon cooling.
